UNITED STATES PATENT OFFICE

FRED C. GRUMMAN, OF NORWALK, CONNECTICUT, ASSIGNOR TO MERGENTHALER LINOTYPE COMPANY, A CORPORATION OF NEW YORK

MATRIX CABINET

Application filed July 8, 1931. Serial No. 549,382.

This invention relates to storage cabinets for matrices used in slug casting machines, and more particularly to a matrix cabinet drawer in which matrices having ears projecting from their opposite edges may be stored on edge.

It is well known to those skilled in the art that the matrices differ in body thickness according to the set width of the characters formed thereon, but that the ears projecting from the edges of the matrices are of a substantially uniform thickness. Thus, the ears of matrices bearing large characters and used for casting large type for newspaper headlines and other display work, are much thinner than the edge of the matrix body from which they project.

For storing matrices of this kind, it has been customary, heretofore, to utilize a cabinet in which the drawers are arranged on a transverse incline, in order that the matrices therein can rest by their projecting ears on the bottom of the drawer and lean against one another so as to be supported in a semi-upright position. However, because of the thinness of the projecting matrix ears, and due to the fact that they are not centered on the edges of the matrices, the latter have a tendency to fall over on their side faces, except in the case of a full compartment. While this tendency is present even with drawers arranged at an inclination, it becomes unavoidable when the drawers are disposed horizontally as is often required. Furthermore, a systematic arrangement of the matrices in the drawer compartments is dependent wholly upon the care and thoroughness of the operator, since the matrices may be placed therein in a number of different positions. In practice, this disarrangement of the matrices has proven itself to be a great annoyance and hindrance to the composer, both in the selection of the matrices from the drawer compartments and in their replacement therein.

It is the object of the present invention, therefore, to obviate the foregoing and other objectionable features, by providing a matrix cabinet with drawers in which matrices having ears of less thickness than that of the

bodies of the matrices and projecting from the edges thereof, may be supported on edge and also in corresponding positions, whether the drawer is horizontal or not.

To this end, the invention contemplates means within the drawer for supporting the matrices on edge independent of their projecting ears. More specifically, the invention provides a drawer divided by longitudinal and transverse partitions into a plurality of compartments, and a raised rib, of less width than that of the compartment, extending longitudinally therein and adapted to support the matrices by their edges, independent of their projecting ears and independent of one another.

In the accompanying drawings, the invention is shown merely by way of example and in preferred form, but obviously many variations and modifications may be made therein which will still be comprised within its spirit. It is to be understood, therefore, that the invention is not to be limited to any specific form or embodiment except in so far as the limitations are specified in the appended claims.

Referring now to the drawings:

Fig. 1 is a perspective view of a matrix cabinet equipped with the improved drawers, and showing one partially withdrawn;

Fig. 2 is a top view of a detached drawer, showing the arrangement of the supporting ribs therein;

Fig. 3 is a fragmentary vertical section taken on the line 3—3 of Fig. 2 looking in the direction of the arrows;

Fig. 4 is a fragmentary vertical section taken on the line 4—4 of Fig. 3 looking in the direction of the arrows; and

Fig. 5 is a vertical section taken through the front wall of a drawer and showing a metal face plate with a handle thereon.

The matrix cabinet A may be of any suitable size and may have any desirable drawer arrangement therein. Preferably, and as shown in Fig. 1, the cabinet is low and rectangular, having a flat top B, bordered by raised side walls b¹, b² and b³. A number of drawers, generally designated by the letter C, are slidably arranged in one end of the

cabinet, and are adapted to hold "sorts" or extra fonts of matrices, which can be conveniently selected from the drawers and assembled by hand either in a suitable hand 5 composing stick, or in the so-called "assembler" of a linotype machine. Each drawer has two side walls c^1 and c^2 , front and rear walls c^3 and c^4 , respectively, and a bottom wall c^5 , the side walls c^1 and c^2 being extended 10 rearwardly as at c^6 and c^7 . A plurality of compartments are defined within the individual drawers by a number of longitudinal partitions c^8 and a number of transverse partitions c^9 , the compartments being of any suitable 15 length and of a width slightly greater than the length of a matrix. In the present instance, the drawers C are arranged horizontally in the cabinet A, the latter being designed for use as an auxiliary matrix equipment for commercial linotype machines.

As will be seen from Figs. 2, 3, and 4, the matrices M are of the regular form having upper and lower ears m and m^1 , respectively, 20 projecting from opposite edges thereof, the ears being of considerably less thickness than that of the bodies of the matrices. It may also be noted that, although the upper and lower ears of the same width, i. e., project the same distance from the edges of the matrices, 25 the upper ears m are considerably longer than the lower ears m^1 .

In carrying out the present invention, a rib D, (see Fig. 3) of less width than the distance between the upper and lower ears on 30 one edge of a matrix, and of a height slightly greater than the projecting width of said ears, is located in each drawer compartment and is formed integrally with or otherwise 35 permanently secured to the bottom wall c^5 . The rib D extends longitudinally of its compartment but is slightly off center so as to provide clearance spaces or grooves E— E^1 , 40 between the opposite edges of the rib D and the longitudinal partitions c^8 , it being noted 45 that the space E which is intended to receive the long upper ears m of the matrices is correspondingly wider than the space E^1 which is intended to receive the shorter ears m^1 of the matrices.

With this arrangement, the matrices can be placed in the drawer in but one position, that is, with all their tops together and all their bottoms together, since the longer upper 50 ears cannot fit in the narrower space E^1 and can only fit in the wider space E. Moreover, the matrices, when placed in the compartment, are supported directly by their edges or independent of their projecting ears, which are too narrow to touch the bottom of the 55 drawer.

Referring to Fig. 2, a novel stop latch S is provided at the rear of the drawer to prevent its complete withdrawal from the cabinet. This latch is supported by an angle-iron bracket S^1 , secured to the inner face of

the side wall extension c^6 , and includes a lever S^2 , pivotally mounted as at s on the bracket S^1 . One arm of the lever S^2 extends forwardly and is located in a recess c^{10} , formed in the rear wall c^4 of the drawer, the extreme 70 end of the arm being turned up to provide an actuating thumb-piece s^1 . The other arm of the lever S^2 is formed with a horizontal depressed end portion s^2 lying substantially in the medial horizontal plane of the side wall extension c^6 .

The lever S^2 is adapted to actuate a stop pin s^3 , which is pivotally connected thereto as at s^4 , and which projects laterally through an opening in the side wall extension c^6 . To 80 hold the pin s^3 normally in a projecting position, there is provided a small tension spring s^5 , secured at one end to the forwardly extending arm of the lever S^2 and at its opposite end to the rear wall c^4 of the drawer.

In use, when the drawer is pulled out, the projecting pin s^3 abuts against the front pillar of the cabinet frame, thereby preventing the drawer from being completely withdrawn unintentionally. However, when it is desired 90 to remove the drawer from the cabinet, the turned-up thumb-piece s^1 has only to be pressed laterally, thereby swinging the lever S^2 and retracting the stop pin s^3 sufficiently to 95 permit it to clear the frame of the cabinet.

As a further feature, the wooden front wall c^3 of the drawer (see Fig. 5) is provided with a metal channeled face plate F. As shown, the front wall is fashioned with two longitudinal grooves c^{11} and c^{12} , to receive the in-turned flanges f and f^1 of the face plate. In attaching the face plate to the front wall, the flanges f and f^1 are alined at one end with the grooves c^{11} and c^{12} , respectively, whereupon it may be slid endwise into position and held in place by its flanges. Incidentally, screws h, which attach a handle H to the face plate, are caused to embed themselves in the wooden front wall c^3 so as to prevent the face plate from sliding laterally out of position.

Having thus described my invention, what I claim is:

1. A matrix cabinet drawer for storing matrices having ears projecting from the edges thereof, and provided with means for supporting the matrices by their edges in an upright position independent of their projecting ears.

2. A matrix cabinet drawer for storing matrices formed on one edge and at opposite ends with projecting ears, and provided with means adapted to fit between the projecting ears to support the matrices by their edges in an upright position independent of said ears and independent of one another.

3. A matrix cabinet drawer for storing matrices formed with ears projecting from the edges of the matrix bodies, said ears being of less thickness than that of the matrix

bodies, said drawer having vertical partitions defining a plurality of compartments, and a device arranged horizontally within each compartment on which the matrices are adapted to be supported by their edges and independent of their projecting ears.

4. A matrix cabinet drawer for storing matrices formed on one edge and at opposite ends with projecting ears, said ears being of different lengths, said drawer having longitudinal and transverse partitions defining a plurality of compartments of slightly greater width than the length of a matrix, and a horizontally disposed rib extending longitudinally of each compartment and being adapted to fit between the projecting ears on the edges of the matrices, the height of said rib being slightly greater than the projecting width of the matrix ears; whereby the matrices are supported in an upright position in the compartments by their edges independent of the projecting ears and independent of one another.

5. A matrix cabinet drawer for storing matrices formed on their edges and at opposite ends with projecting ears, said ears at opposite ends being of different lengths, said drawer having partitions defining a plurality of compartments, and a device in each compartment for supporting the matrices and arranged relative to the partitions to prevent the matrices from coming to their final supporting position on said device unless similarly positioned in the compartment.

6. A matrix cabinet drawer for storing matrices formed on their edges and at opposite ends with projecting ears, said ears being of different lengths, said drawer having partitions defining a plurality of compartments, and a rib extending longitudinally of each compartment and arranged to form spaces of unequal widths between its opposite edges and the partition walls, the spaces being of such widths that the longer matrix ear will fit in the wider space only, thereby causing all the matrices to be positioned similarly in the drawer.

7. A matrix cabinet drawer as described in claim 4, wherein the matrix supporting ribs are located off center in the compartments, thereby compelling similar positioning of the matrices in the drawer.

8. A matrix cabinet drawer having partitions defining a plurality of compartments therein in which matrices are adapted to be stored, said drawer having a front wall provided on its top and bottom edges with longitudinal grooves in which turned-in inner edges of a channeled face plate are adapted to fit, thereby permitting said face plate to be slid laterally into position and to be held in position thereby.

9. A matrix cabinet drawer for storing matrices formed on their edges with projecting ears, said matrices having distinguish-

able tops and bottoms, and means to prevent the matrices from coming to properly supported position in the drawer unless similarly positioned therein with respect to their tops and bottoms.

10. A matrix cabinet drawer for storing matrices having distinguishable top and bottom edges, said drawer being horizontally disposed and open at the top, and means within the drawer to determine the positioning of the matrices therein, characterized by the fact that the matrices are prevented thereby from coming to properly supported position in the drawer unless similarly positioned therein with respect to their top and bottom edges.

In testimony whereof, this specification has been duly signed by:

FRED C. GRUMMAN.
